(57) **CLAIM**

The ornamental design for a shoe accessory, as shown and described.

DESCRIPTION

This Design Patent Application is related to the following commonly owned and assigned applications: U.S. Design patent application Ser. No. 29/258,102, “Shoe Accessory,” filed herewith; U.S. Design patent application Ser. No. 29/258,101, “Shoe Accessory,” filed herewith; and U.S. patent application Ser. No. 11/408,130, “System and Method for Securing Accessories to Clothing,” filed on Apr. 20, 2006.

FIG. 1 is a perspective view of a shoe accessory showing our new design;

FIG. 2 is a top plan view thereof;

FIG. 3 is a bottom view thereof;

FIG. 4 is a front elevational view thereof;

FIG. 5 is a rear elevational view thereof; and,

FIG. 6 is a side elevational view thereof; the opposite side being a mirror image.

The portion of the article depicted in broken lines is for illustrative purposes only and forms no part of the claimed design.
